(57) **CLAIM**

The ornamental design for a hood portion for a floor cleaner, as shown and described.

DESCRIPTION

FIG. 1 is a top, front and right side perspective view of a hood portion for a floor cleaner showing my new design; FIG. 2 is a top, front and right side perspective view without the handle portion of the vacuum cleaner shown in broken lines of FIG. 1 thereof; FIG. 3 is a top plan view thereof; FIG. 4 is a front view thereof; FIG. 5 is a right side elevational view thereof; FIG. 6 is a left side elevational view thereof; and, FIG. 7 is a rear view thereof.

The portion of the vacuum cleaner shown in broken lines in the figures is for illustrative purposes only and forms no part of the claimed design.
